UNITED STATES PATENT OFFICE.

CHARLES NATHANIEL TAYLOR, OF HEMINGFORD, NEBRASKA.

DITCHING, GRADING, AND BACK-FILLING MACHINE.

Application filed July 11, 1922. Serial No. 574,306.

To all whom it may concern:

Be it known that CHARLES NATHANIEL TAYLOR, a citizen of the United States of America, residing at Hemingford, in the 5 county of Box Butte and State of Nebraska, has invented new and useful Improvements in Ditching, Grading, and Back-Filling Machines, of which the following is a specification.

10 The object of the invention is to provide a machine of the type ordinarily employed for ditching and grading wherein the scoops are mounted for movement in paths transverse to that of the machine and respectively 15 in advance of and following the machine or the supporting truck therefor for opening the path for the machine truck to the end that the mechanism may operate in a substantially uniform plane in its progressive movement and furthermore to economize in the expenditure of power and time in the removal of the soil by arranging the scoops and the 20 means for operating the same to successively traverse the same path in opposite directions 25 and in alternate relation; and to provide efficient joint means for successively dumping the scoops with relative uniformity and under the control of an operator positioned 30 to control the truck mechanism and the motor by which the same is actuated; and with these objects in view the invention consists in a construction and combination of parts of which a preferred embodiment is shown in the accompanying drawings, 35 wherein:—

Figure 1 is a plan view, and

Figure 2 is a side view of a mechanism embodying the invention.

40 Figure 3 is a perspective view illustrating the method by which the machine is advanced in operation.

Figure 4 is a detail view of a portion of the traction cable.

45 Figure 5 is a detail view illustrating a supplemental traction cable.

The framework of the machine embodies essentially a truck 10 consisting in the construction illustrated of the longitudinal beams 11 supported by the axially pivotal wheels 12 of 50 conventional form and mounting and a bracing wheel 13 carried by an extension frame 14 and mounted upon a fixed spindle to follow a path in substantial parallelism with the main wheels 12, and a superstructure carried by the truck and having an upright or 55 mast 15 suitably braced, with a boom 16

pivotal for adjustment in angular position on the truck and held in the desired position by a guy-cable 17 extending over a pulley 18 on the mast for operation 60 by a drum 19. Extending in opposite directions laterally and rearwardly from the truck are front and rear spacing arms 20 provided terminally with pulleys 21 for the hoisting cable 22, terminally reeled upon the 65 hoisting drum 23 and extending from the extremities of the spacing arms forwardly on convergent lines to and around a direction pulley 24 near the outer end of the boom. The scoops 25 of which one or more may be 70 employed for each run of the hoisting cable, a run being referred to as the portion of the cable between each guy-pulley 21 and the direction pulley 24, are connected with the hoisting cable by front and rear chains 26 75 and 27 or similar flexible means suitable for the purpose indicated, the former being connected in each instance as at 28 to permit of the tilting and direction of the scoop by means of the manually operable handles 29 80 adapted to be grasped by the attendants or assistants of which one is required for each scoop.

Pivotal for swinging movement in a vertical plane in a suitable fork 30 at 85 the free end of the boom is a dumping bar 31 from the lower end of which extends an operating cable 32, preferably around one or more intermediate guy-pulleys 33 on the boom to an operating drum 34 which in the 90 construction illustrated and preferably is located in co-axial relation with the hoisting drum 23 and is within convenient control of an engineer or other operative stationed on the seat 35 and therefore in a position to 95 clearly observe the operations of all of the scoops.

Extending around the guy-pulley 36 carried by the upper end of the dumping bar is what may be termed a continuous dumping cable 37 in that its terminals are connected with the hoisting cable at the points of connection of the rear chains 27 of the scoops with said hoisting cable, to the end that when the dumping cable is tensioned by 100 the tilting of the dumping bar through the tensioning of the operating cable 32, it operates to tilt and dump the scoop which is loaded and which is advancing in the direction of the arrow *a* in Figure 1, because the 105 portion of the hoisting cable in rear of the loaded bucket is slack owing to the fact that

the scoop traversing the opposite path or on the other run of the hoisting cable as indicated by the arrow *b*, is retracing its movement or is proceeding rearwardly, after being emptied or dumped, preparatory to receiving a fresh load.

Assuming that the direction of progress of the ditching or grading operation is as indicated by the arrow *c* on Figure 1, it will be obvious that the scoop which is actuated by that run of the hoisting cable which is in advance of the truck will serve to remove soil in the path of the truck to prepare a way therefor while the scoop operating in connection with the other run of the hoisting cable will complete the operation to the required depth, and the progress of the truck therefore may be at a comparatively uniform level, and may be effected for example by the stretching of a cable 38 parallel with the path desired for its progress and making connection between stepped or spaced rings 39 thereof, arranged at any suitable intervals adapted for the advance of the truck from time to time, and the hoisting drum or the equivalent thereof through a supplemental traction cable 40, so as to move the machine the required distance in a step by step manner as the work proceeds, said arrangement of the advancing cables being indicated in Figure 3.

Having described the invention, what is claimed as new and useful is:—

1. A machine of the type indicated having a truck carrying a laterally extending boom, and a scoop carrying hoisting cable provided with runs extending transversely respectively in front and in rear of the truck and between the longitudinal plane of the latter and the outer end of the boom and on transversely convergent lines.

2. A machine of the type indicated having a longitudinally movable truck, a boom carried by and extending laterally in one direction from the truck, and front and rear arms extending laterally in the opposite direction from the truck, said boom and arms being provided with terminal guiding means, and a scoop carrying hoisting cable traversing said guiding means and having runs extending from the extremities of said arms in convergent relations toward the guiding means of the boom.

3. A machine of the type indicated having a longitudinally movable truck, a boom carried by and extending laterally in one direction from the truck, and front and rear arms extending laterally in the opposite direction from the truck, said boom and arms being provided with terminal guiding means, and a scoop carrying hoisting cable traversing said guiding means and having runs extending from the extremities of said arms in convergent relations toward the guiding means of the boom, reversible

means being provided for actuating the cable to impart motion thereto alternately in opposite directions.

4. A machine of the type indicated having a longitudinally movable truck, a boom carried by and extending laterally in one direction from the truck, and front and rear arms extending laterally in the opposite direction from the truck, said boom and arms being provided with terminal guiding means, and a scoop carrying hoisting cable traversing said guiding means and having runs extending from the extremities of said arms in convergent relations toward the guiding means of the boom, said cable being reversible, and a scoop dumping means consisting of a continuous cable connecting the scoops and extending to the outer end of the boom, and a tensioning device for straining said dumping cable.

5. A machine of the type indicated having a longitudinally movable truck, a boom carried by and extending laterally in one direction from the truck, and front and rear arms extending laterally in the opposite direction from the truck, said boom and arms being provided with terminal guiding means, and a scoop carrying hoisting cable traversing said guiding means and having runs extending from the extremities of said arms in convergent relations toward the guiding means of the boom, and a scoop dumping means having a cable-guide located near the outer end of the boom, a continuous dumping cable terminally connected with the hoisting cable adjacent to the rear ends of the scoops and extending through said guide, and means for operating the guide to tension the dumping cable.

6. A machine of the type indicated having a longitudinally movable truck, a boom carried by and extending laterally in one direction from the truck, and front and rear arms extending laterally in the opposite direction from the truck, said boom and arms being provided with terminal guiding means, and a scoop carrying hoisting cable traversing said guiding means and having runs extending from the extremities of said arms in convergent relations toward the guiding means of the boom, and dumping means consisting of a pivotal dumping bar mounted upon the bar and carrying a cable guide, a continuous dumping cable terminally connected with the scoops and extending through said guide, and means for tilting the dumping bar to tension the dumping cable.

7. A machine of the type indicated having a longitudinally movable truck, a boom carried by and extending laterally in one direction from the truck, and front and rear arms extending laterally in the opposite direction from the truck, said boom and arms being provided with terminal guiding

means, and a scoop carrying hoisting cable traversing said guiding means and having runs extending from the extremities of said arms in convergent relations toward the 5 guiding means of the boom, and dumping means consisting of a pivotal dumping bar mounted upon the bar and carrying a cable guide, a continuous dumping cable terminally connected with the scoops and extending through said guide, and means for tilting the dumping bar to tension the dumping cable, and a drum actuated operating cable for tilting the dumping bar to tension the dumping cable.

15 8. A machine of the type indicated having a longitudinally movable truck, a boom carried by and extending laterally in one direction from the truck, and front and rear

arms extending laterally in the opposite direction from the truck, said boom and arms being provided with terminal guiding 20 means, and a scoop carrying hoisting cable traversing said guiding means and having runs extending from the extremities of said arms in convergent relations toward the guiding means of the boom, the scoops being 25 flexibly connected with the hoisting cable, and dumping means for the scoops having a looped dumping cable terminally connected with the hoisting cable adjacent to the connection therewith of the rear ends 30 of the scoops and means for tensioning the dumping cable.

In testimony whereof he affixes his signature.

CHARLES NATHANIEL TAYLOR.
